BED STRUCTURE

Solomon Raduns, Brooklyn, N. Y., assignor to
Greenpoint Metallic Bed Company, Inc.,
Brooklyn, N. Y.

Refiled for abandoned application Serial No.
91,071, July 17, 1936. This application April
25, 1938, Serial No. 204,151

1 Claim. (Cl. 5—209)

The present invention has as its principal aim the provision of a spring structure for use with beds, although certain features of the invention may be found to be desirable in other cases where mattresses or cushions or padding are to be used upon the spring, so that while for the sake of brevity the title of the invention is given as "Bed structure" it is intended that such title be all comprehensive as it were so as to include the adaptability of the invention to other bases than is furnished by a bedstead, cot or the like.

In connection with bedsteads which ordinarily includes side rails and ends attached to the side rails, preferably detachably, the invention from a broad point of view provides a mattress or cushioning receiving top supported by a frame of suitable construction, and movable elements supported from opposite sides of the frame, each of which elements is adjustable independently of the other such elements, and which may be rigidly fixed in their adjusted position relatively to such frame, thereby providing movable elements which may be brought into contact or bearing relation at preferably four points with the lateral surfaces of the base or bedstead which is adapted to support the frame, whereby such frame may be centralized or oriented symmetrically with respect to the base or bedstead to prevent lateral shifting of the frame relatively to the base.

Such a centralizable spring or the like is new in the art, as the make-shift devices of the prior art, while adapted to support such a spring or the like from a base, do not in association therewith serve to centralize the spring or the like with respect to the base, that is, do not so support the spring or the like that the latter "stays put," inasmuch as by the use of the present invention any lateral shifting of the frame relatively to the base is prevented; that is, it may be prevented whenever desired if the spring is in the first instance adjusted to the desired definite position.

The improvements of the present invention adapt the spring structure for a more or less universal adjustment and centralizing thereof, that is a given size of spring structure, with respect to bases and more particularly bedsteads which are of different types of construction, no change in such construction being necessitated when the universally adjustable spring of the present invention is used. In connection with beds it is stated that the United States Department of Commerce has issued schedules recommending standard sizes for metal and wood beds,

indicating the different dimensions of such beds to accommodate coil springs and link springs of given dimensions of such springs, showing that in connection with link springs, for example, diverse dimensions thereof are recommended for metal beds and wood beds of relatively different dimensions, and this practice when followed would mean that each link spring of given dimensions would have to be differently constructed and proportioned to go onto metal and wood beds of different dimensions adapted to receive such link springs of given dimensions.

Under the present invention the principal aim is to so construct a link spring that it may be fitted to metal beds and wood beds of different dimensions without having to change the construction of the link spring whereby the latter is so adapted.

These being among the objects of the present invention, the same consists of certain features of construction and combinations of parts to be hereinafter described and then claimed with reference to the accompanying drawings illustrating a preferred embodiment of the invention as applied, but not necessarily, to metal and wood beds, and wherein

Fig. 1 is a plan showing a link spring provided with the present improvements, and which is shown as broken transversely through the bedstead and broken longitudinally through the bedstead, parts being omitted for the sake of clearness;

Fig. 2 is a longitudinal section on the line 2—2, 35 Fig. 1, showing one of the side rails of a bedstead broken away, and parts being in elevation;

Fig. 3 is a vertical section on the line 3—3, Fig. 2, showing two side rails, the view being broken away in its middle portion;

Fig. 4 is a sectional elevation showing the same parts as shown to the left of Fig. 3, but illustrating the improvements as applied to metal bedsteads having side rails of angle metal with the horizontal flange of each located at the bottom of the rail, whereas in Figs. 1, 2 and 3 it is located at the top of the rail;

Fig. 5 is a view similar to Fig. 4, except that the improvements are shown as adapted to a bedstead with wood side rails;

Fig. 6 is a view similar to Fig. 5, except that the improvements are shown as adapted to a wood bedstead provided with old fashion slats; and

Fig. 7 is an enlarged perspective view of one of the adjustable elements or members slidably

mounted on one of the supporting brackets, which is partly shown in broken lines.

Referring to Figs. 1, 2 and 3, parts of a metal bedstead are illustrated, including angle metal side rails 10, 11 which are provided at opposite ends with well known tapering bosses or ribs 12 which are inserted into the socket portions 13 at each end of the end pieces 14 forming the head and foot of the bed, whereby to detachably connect the parts together in well known manner. In these figures of the drawings the angle metal rails 10, 11 are shown with their horizontal flanges extending inwardly from the upper edges of the vertical flanges, so that the corner of the angle metal is at the top of the rail.

The illustrated bed bottom or spring provided with the present improvements includes cross pieces 15, 16 at the opposite ends and which are preferably formed of angle metal, each with a horizontal flange 17 and a vertical flange 18, these cross pieces 15, 16 being parallel with each other and the horizontal flanges 17 being directed inwardly towards each other. A pair of preferably cast metal brackets 19 is fixed one at each end of the cross piece 15 and a similar pair of brackets 20 is fixed, one to each end, of the cross-piece 16, although the drawings illustrate but one of the brackets 20. It will be readily understood that the bracket 20 which is omitted from the upper right hand corner of Fig. 1 will correspond to that one of the brackets 19 which is located longitudinally away from it on the spring frame, such omitted bracket 20 in other words corresponding to that one of the pair of brackets 19 shown in Fig. 3 which is located to the left of Fig. 3.

The brackets 19, 20 preferably extend downwardly from the cross-pieces 15, 16 and their lower ends are disposed inwardly with respect to the vertical planes of the flanges 18 which is preferably accomplished by curving the brackets 19, 20 in opposite directions outwardly away from their lower ends. In order to secure each bracket to its proper cross piece, the upper end of each is provided with a mounting plate 21 which is placed against the inner surface of the appropriate flange 18, and then each plate is preferably riveted to such flange, preferably two rivets being employed so as to rigidly retain each bracket 19, 20 in a plane to extend at right angles to the plane of the upper flanges of the cross pieces 15, 16. At the lower end of each bracket 19 and 20 there is formed a socket 22, and the sockets of the respective brackets 19, 20 receive the ends of metal side bars 23, which are rigidly secured therein as by a friction fit or otherwise, as desired. The parallel side bars 23 may each be formed with a metal tube of cylindrical shape for the sake of lightness, although the cross-sections of the side bars and of the sockets 22 need not be cylindrical. These side bars 23, the brackets 19, 20 and the cross-pieces 15, 16 thus preferably constitute a rigid frame.

As the illustrated frame 15, 16, etc., is constructed to adapt it for supporting link springs, there is illustrated a wire-link fabric top 24 (Fig. 1) which may be of any suitable construction and connected at opposite ends thereof, by means of helical tension springs 25, with the horizontal flanges 17 of the cross-pieces, such flanges being perforated in the usual manner to receive hooks at the ends of the tension springs 25. Thus the top 24 is made flexible and resili-

ent so as to constitute a supporting spring for a mattress or the like.

At the outer ends of the sockets 22 they are closed by abutments or seats 26, preferably formed integrally with the brackets and which are arranged in parallel vertical planes. Parallel shoulders 27, 28 are formed on each bracket to extend beyond the abutment or seat 26, these shoulders extending horizontally in the direction of the width of the frame 15, 16, etc. Each pair of shoulders 27, 28 provides a guide-way between them, and if desired the shoulders and the guideway may be differently constructed for accomplishing the ultimate end in view. There will hence be four pairs of shoulders corresponding with the four brackets in the preferable construction, and between the shoulders of each pair there is mounted a movable elongated metallic member 29, as shown in perspective in Fig. 7.

Each movable member 29 is preferably of plate form or type and the plate portion 30 is preferably set on edge to stand vertically between the shoulders 27, 28 of each pair of shoulders, and there will hence preferably be four of the metallic members 29. Preferably the thickness of each plate portion 30 corresponds to the depth of the groove formed between the shoulders 27, 28 so that its outer surface is flush with the corresponding surfaces of the shoulders. These metallic members 29 should be strong and durable as they are adapted to constitute the supports for the frame 15, 16, etc., upon a supporting base or bedstead. Also to this and preferably each of the plates 30 is provided with a reinforcing edge portion 31 which gradually tapers from the lower edge of the plate portion 30 in a curve so as to merge with the upper edge of the plate portion. That is, the upper edge of the plate portion and its outer end are reinforced and strengthened by an edge portion 31 which gradually enlarges in width from the top of the plate portion, and where it passes the lower edge of the plate portion it forms a downwardly projecting toe 32, that is, a toe which is located at the outer end of each movable member 29 and which preferably projects at right angles thereto.

Each of the preferably four movable members 29 is provided with a longitudinal slot 33 of suitable length, preferably at least one and three-quarters inches, so that a set-screw with a head 34 and a screw stem 35 may be engaged with the movable member, the screw stem 35 being screwed into a screw threaded hole at the center of the abutment or seat 26. It will therefore be seen that each movable member 29 may be moved outwardly or inwardly to adjust its toe 32 to a desired position, and when the set-screws are tightened up, the head 34 of each will be brought to bear firmly upon the outer surface of the corresponding movable member 29, thereby releasably securing the movable member 29 positively in a predetermined position.

According to the present disclosure there will therefore be at least four movable members 29, one of each being located at a corresponding corner of the frame 15, 16, etc., or more specifically there will be a pair of the movable members 29 at each end of the frame 15, 16, etc., which extend outwardly, so that there is a pair adjacent to and parallel with the cross-piece 15 and another pair of the members 29 adjacent to and parallel with the cross-piece 16, as shown more

clearly in Fig. 1. It is clear therefore that the movable members 29 may be adjusted in one horizontal plane which is parallel with and below the plane of the top 24, 25, whatever the construction of the top may be.

It is to be understood that exactly the same dimensions and construction of frame 15, 16, etc., with whatever form of top said frame supports, may be supported, positioned and centralized or oriented with whatever dimensions of base or bedstead are required for a removable frame for the differently constructed bases or bedsteads. The drawings illustrate the bottom frame or spring as applied to bedsteads of four different constructions, and it is to be understood that if the invention is to be adapted to bases or bedsteads of different dimensions from the ones to which a given size of removable frame or spring may be applied, it will still be applicable universally to other different sizes to receive a given size of removable frame or spring. In Figs. 1, 2 and 3 the removable frame or spring has been shown as applied to and centered with respect to a base or bedstead having side rails whereof the horizontal flanges extend inwardly from the upper edges of the vertical flanges. In such case the movable members 29 are adjusted outwardly a slight distance from the brackets supporting them so that the outer ends of the slots 33 will be located somewhat in advance of the set-screws 34, 35, and the toes 32 of the movable members 29 will be engaged over the outer surfaces of the rails 10, 11, at points opposite to the horizontal flanges of said rails. When the parts have been so adjusted and the screws or fastenings 34, 35 set to lock or secure the movable members 29 in their adjusted position, the engagement of the inner surfaces of the toes 32 with the outer surfaces of the rails 10, 11 will positively act to prevent any lateral shifting of the removable frame or spring with respect to the base on which it is supported, inasmuch as preferably there are four points of contact with said rails, two points of contact at each side of the bed or other base, and thereby the removable frame or spring is held centralized with respect to the supporting base, as it cannot be shifted laterally thereof at either end, without first loosening the fastenings or set-screws 34, 35. Therefore, by utilizing the present invention each side of the removable spring structure is prevented from moving inwardly away from a side rail as it is not supported in such manner as to allow the spring to fall at that side, and furthermore the spring structure is prevented from being twisted laterally of itself in such way as to dismount one of the movable members 29 from the side rail or the like on which it is supported.

In Fig. 4 of the drawings the same removable frame or spring construction as described with respect to Figs. 1, 2 and 3 is shown as supported by the horizontal flanges of side rails, such as rail 36, wherein the horizontal flange extends inwardly of the rail beyond the lower edge of its vertical flange. In such an installation, the removable frame or spring structure is set at a lower level than in Figs. 1, 2 and 3, because the toes 32 or the ends of the movable elements 29 are in contact with the inner surfaces of vertical flanges of rails such as 36, and the lower ends of the toes would be resting upon the horizontal flanges of such rails, thereby supporting the frame or spring structure, while at the same time the latter is centralized with respect to the side rails. Inasmuch as the thickness of the metal side rails of

bedsteads is usually a quarter of an inch, the adjustment of each of the movable members in Fig. 3 is approximately a quarter of an inch further out than in Fig. 4. Hence in Fig. 4 the closed outer ends of the slots 33 would be in direct abutment with the set-screws or fastenings, as the removable elements are here shown adjusted inwardly to innermost limit.

In Fig. 5 the improved removable frame or spring structure is shown as installed on a bedstead whereof each of the side rails 37 is of wood. As made by different manufacturers the thickness of each wooden side rail may vary, but as the dimension between the outer surface of the side rails even in such cases usually remains the same, with each wood side rail at least an inch in thickness, the movable elements 29 are shown as adjusted outwardly to their utmost limits. In this case the spring structure would be supported by the movable members 29, while the inner surfaces of the toes 32 will be in bearing contact with the outer surfaces of such rails as 37, at the upper portions of the rails. In this instance the removable spring structure would be centralized with respect to the wood bed structure in the same manner as in Figs. 1, 2 and 3, except that the toes engage wood side rails instead of metal side rails.

In Fig. 6 the removable frame or spring structure is shown as installed on a bedstead with wood side rails, such as rail 38, between which rail and the corresponding rail, not shown, transverse slats 39 of old fashion are employed. In this instance the removable frame or spring structure is supported upon the slats, such as 39, which are behind the slat 39 which is shown, by resting the side bars 23 of the frame upon the outer ends of such slats, while the toes 32 would be located between adjacent slats, but the outer surfaces of the toes or the outer ends of the movable members 29 would be in contact with the inner surfaces of the wood side rails, such as rail 38. In this way the removable frame or spring structure is vertically supported upon the slats without using the movable members 29 as supports, the outer ends of the latter contacting with the inner surface of the side rails so as to centralize and orient the removable frame properly with respect to the bedstead. Hence the movable members 29 may either constitute supports for the removable frame or spring structure or they may merely constitute movable elements or members which contact with lateral surfaces of the bedstead or other base. In Fig. 6 the movable elements 29 are adjusted to intermediate positions, that is to say, each set-screw passes through the slot 33 near the midlength thereof.

From the description and drawings herein it is apparent that in Figs. 3 and 5 the laterally contacting parts such as the depending toes 32 engage with the outer lateral surfaces of the supporting base, thus illustrating two ways in which the invention may be utilized, and if it was not for the fact that it is preferable to use the movable members for obtaining a centralizing of the spring structure in at least two more ways such as shown in Figs. 4 and 6, the depending toes 32 might be omitted, inasmuch as in the two figures last mentioned it is really the outer ends of the movable members of elements which provide the lateral contact.

It will be readily understood by those skilled in this art that the invention as illustrated and described is susceptible of more or less modification

without departing from the scope of the appended claim, and it is to be clearly understood that while the introductory clause of a claim may refer to a bed structure, that the invention may be used in other connections, and such introductory clause is intended to be all comprehensive as it were, and is not used as a limitation, except where required by the substance or essential features of a claim.

The present application is a refile for application Serial No. 91,071, filed July 17, 1936, which application became abandoned March 3, 1937.

What I claim as new is:

In a rectangular spring construction, an adjustable support connection to support said rectangular spring construction upon the side rails of metal and wood bed frames, said side rails being of rectangular and right angular cross sections, said rectangular spring construction including a rectangular frame, and also including

10 downwardly extending brackets, said connection comprising a seat formed in the side of the lower end of one of said brackets, a slotted sliding bar fitting in said seat, the axis of said bar being horizontally disposed and being transverse to the axes of the side rails and the plane of said bar being vertical, and a bolt extending through said slot and fixed in said seat to fix said bar in an adjusted position, said seat having upper and lower guiding projections closely fitting the upper and lower edges of said bar and said bar having a downwardly projecting lip extending transversely across the outer end of said bar, said lip fitting on the corner or over the corner of said rails of right angular cross section and fitting over the corner of side rails of rectangular cross section, the upper edge of said bar being widened and turned downwardly adjacent its outer end to form said lip.

SOLOMON RADUNS.
